Primary Examiner — Zenia I Bennett(74) *Attorney, Agent, or Firm* — Dawsey Co., LPA;
David J. Dawsey(57) **CLAIM**

The ornamental design for an action figure, as shown and described.

DESCRIPTION

FIG. 1 is a front elevation view of an embodiment of the design;

FIG. 2 is rear elevation view of an embodiment of the design;

FIG. 3 is a right side elevation view of an embodiment of the design;

FIG. 4 is a left side elevation view of an embodiment of the design;

FIG. 5 is a top plan view of an embodiment of the design; and,

FIG. 6 is a bottom plan view of an embodiment of the design.

The broken lines show unclaimed subject matter only and form no part of the claimed design.

1 Claim, 3 Drawing Sheets(56)
